UNITED STATES PATENT OFFICE.

OWEN W. MALONEY, OF TULSA, OKLAHOMA.

TOY GUN.

1,168,950.

Specification of Letters Patent. Patented Jan. 18, 1916.

Application filed March 26, 1915. Serial No. 17,189.

To all whom it may concern:

Be it known that I, OWEN W. MALONEY, a citizen of the United States, and a resident of Tulsa, in the county of Tulsa and State 5 of Oklahoma, have invented certain new and useful Improvements in Toy Guns, of which the following is a specification.

The present invention relates to toys, and more particularly to a toy gun adapted for 10 use in shooting small projectiles therefrom such as marbles, rubber balls and the like.

Briefly stated, the invention comprises a stock to which are secured a pair of pivoted members, the free ends of which are normally held together by trigger mechanism.

A spring is coiled about the pivots and has its terminals engaging the free ends of said members so that when the trigger mechanism is actuated the members are forcibly 15 spread apart and operate to eject a projectile from a propelling device secured to the members adjacent the free ends thereof.

The inventive idea involved is capable of receiving a variety of mechanical expressions, one of which, for the purpose of illustrating the invention, is shown in the accompanying drawing; but it is to be expressly understood that the particular construction shown in the drawing is used only for facilitating the description of the invention as a 20 whole and not for defining the limits thereof, reference being had to the appended claims for this purpose.

In the drawing: Figure 1 is a top plan 25 view of the invention; Fig. 2 is a longitudinal section on the line 2—2 of Fig. 1; Fig. 3 is a transverse section on the line 3—3 of Fig. 2; and Fig. 4 is a perspective view of the invention showing the pivoted members 40 thereof spread apart.

Referring more particularly to the accompanying drawings, in which like reference characters designate similar parts, the numeral 5 indicates a stock having a suitable handle 6 formed integrally therewith and extending laterally at right angles thereto. The stock 5 is provided with a pair of adjacent pivot pins 7, each adapted to receive one end of a member 8 which is preferably made of metal and of channeled formation. Each member 8 is provided upon its upper face with a cut out portion 9 so that when the members are in the position shown in Fig. 1 said cut out portions 55 will form an opening large enough for the

reception of a projectile 10. The stock 5 is provided on the under side thereof with an elongated aperture 11 in which is pivoted at 12 a trigger 13 in the form of a bell crank lever. The trigger 13 has pivoted at 60 one end thereof a small upright 14 which extends upwardly through an opening 15 communicating with the elongated aperture 11. The upper end of the upright 14 is provided with a transversely extending arm 16, 65 each end of which is provided with a small projection 17 adapted to engage an opening 18 formed in the under face of each of the channeled members 8. When the parts are in the position shown in Fig. 1, the projections 17 are in engagement with the members 8 and retain them in this position. A small coiled spring 14 is mounted in the opening 15 and has one end secured to the stock while the other end is secured in the upright 14 70 whereby the arm 16 is yieldably retained in the position illustrated in Fig. 3, the operation of the trigger 13 being against the tension of the said spring.

Each of the members 8 is provided in the free end thereof with a stud or pivot 20 to which is secured one end of a projectile propelling device 21 in the form of a sling. This sling 21 is preferably made of some strong flexible material such as leather and 80 is adapted to assume the form of a loop, when the parts are in the position illustrated in Fig. 1, in order to receive the projectile 10.

A strong spring 22 is coiled intermediate 90 its ends about each of the pivots 7 and the terminals 23 of said spring extend along and engage the inner side of the bottom of the channeled members 8 whereby the free ends thereof are forced apart into the position 95 shown in Fig. 4 when the trigger is operated to withdraw the projections 17 from the openings 18 in said members. It will be apparent that when the members are released as just described the sling 21 will be forcibly 100 straightened, as shown in Fig. 4, and the projectile 10 will be forcibly propelled therefrom.

Having thus described the invention, what is claimed is:—

1. A device of the character described comprising pivoted members, means releasably engaging said members for retaining the free ends thereof together, a projectile propelling device carried by said members, 110

and means for ejecting the projectile from said propelling device when said releasable means is actuated.

5. A device of the character described comprising a pair of channeled members pivoted at adjacent ends thereof, means releasably engaging said members for retaining the free ends thereof together, a projectile propelling device carried by said members, and means for ejecting the projectile from said propelling device when said releasable means is actuated.

10. 3. A device of the character described comprising a pair of channeled members pivoted at adjacent ends thereof, means releasably engaging said members for retaining the free ends thereof together, a projectile propelling device carried by said members, and means engaging said members for forcing them apart to eject the projectile from said propelling device when said releasable means is actuated.

15. 4. A device of the character described comprising a pair of channeled members pivoted at adjacent ends thereof, means releasably engaging said members for retaining the free ends thereof together, a projectile propelling device carried by said members, and a trigger for operating said releasable means.

20. 5. In a device of the character described, the combination of a stock, pivoted members secured at one end thereof to said stock, releasable means for retaining the other ends of said members together, means for actuating said releasable means, and means for propelling a projectile from said members when the releasable means is operated.

25. 6. In a device of the character described, the combination of a stock, pivoted members secured at one end thereof to said stock, releasable means carried by said stock for retaining the other ends of said members together, means for actuating said releasable means, and means for propelling a projectile from said members when said releasable means is operated.

30. 7. In a device of the character described, the combination of a stock, pivoted members secured at one end thereof to said stock, releasable means for retaining the other ends of said members together, means for forcing the free ends of said members apart when the releasable means is actuated, and means for propelling a projectile from said members when the latter are forced apart.

35. 8. In a device of the character described, the combination of a stock, pivoted members secured at one end thereof to said stock, re-

leasable means for retaining the other ends 60 of said members together, means for actuating said releasable means, means for forcing the free ends of said members apart when the releasable means is actuated, and means carried by said members for propelling a projectile therefrom when the same 65 are forced apart.

9. In a device of the character described, the combination of a stock, pivoted members secured at one end thereof to said stock, releasable means for retaining the other ends 70 of said members together, means for forcing the free ends of said members apart when the releasable means is actuated, and flexible means carried by said members for propelling the projectile therefrom when the same 75 are forced apart.

10. In a device of the character described, the combination of a stock, a pair of members pivoted thereto, a trigger mechanism 80 carried by the stock and engaging said members to retain the free ends thereof together, a spring engaging said members to force them apart, when the trigger mechanism is actuated, and a flexible sling carried by 85 said members.

11. In a device of the character described, the combination of a stock, a pair of channeled members pivoted thereto, a trigger mechanism carried by the stock and engaging 90 said members to retain the free ends thereof together, a spring coiled intermediate the ends thereof about the pivots of said members and having its terminals engaging said members to force the same apart when 95 the trigger mechanism is actuated, and a flexible sling connected to the free ends of said pivoted members.

12. In a device of the character described, the combination of a stock, a pair of channeled members pivoted to said stock and provided with oppositely disposed cut out portions forming an aperture for the reception 100 of a projectile, a trigger mechanism carried by the stock and engaging said members to retain the free ends thereof together, a spring for forcing said members apart when the trigger mechanism is actuated, and a flexible propelling device carried by said 105 members for ejecting said projectile therefrom.

13. In a device of the character described, the combination of a stock having a handle formed thereon, trigger controlled members pivoted to said stock, and projectile propelling means carried by said members and actuated by the operation thereof.

OWEN W. MALONEY.
